UNITED STATES PATENT OFFICE.

EDWIN T. GREENFIELD, OF KIAMESHA, NEW YORK, ASSIGNOR TO GREENFIELD AUTOMATIC FASTENER COMPANY, OF NEW YORK, N. Y., A CORPORATION OF NEW YORK.

STAPLING-MACHINE.

1,024,889.

Specification of Letters Patent. Patented Apr. 30, 1912.

Application filed June 23, 1911. Serial No. 634,949.

To all whom it may concern:

Be it known that I, EDWIN T. GREENFIELD, a citizen of the United States, and resident of Kianiesha, county of Sullivan, 5 and State of New York, have made a new and useful Invention in Stapling-Machines, of which the following is a specification.

My invention is directed particularly to an improvement in stapling machines such 10 as are disclosed in prior patents granted to me on the 1st day of December, 1896 and 12th day of October, 1909, and numbered respectively 572,293 and 936,996, and it has for its objects—first, to provide holding 15 means for preventing the last staple of a staple strip of the kind utilized in such machines from clogging the outlet of the machine; and second, to so construct such holding means that the last staple of the strip 20 may be utilized.

As disclosed in my prior Patent No. 936,996, it often occurs in using a machine like that illustrated in my earlier Patent No. 572,293 that the last staple of a strip 25 will turn and choke up the outlet of the machine, so that it can only again be used after such staple is dislodged, this objectionable feature constituting a serious aggravation. In my Patent No. 936,996, I have disclosed 30 a means for overcoming these objections by utilizing a feed pawl below the staple strip and a holding pawl above the same and so arranged that the feed pawl yieldingly holds each staple to be severed in the outlet so that 35 the last staple cannot fall or choke the machine and may be driven and clenched.

My present improvement is more especially applicable in connection with the machine disclosed in my earlier patent although it may be utilized with stapling 40 machines generally which successively sever staples integrally united together in strip form.

For a full and clear understanding of my 45 invention such as will enable others skilled in the art to construct and use the same, reference is had to the accompanying drawings in which—

Figure 1 is a longitudinal sectional view 50 taken through a stapling machine illustrating my improvement as applied thereto, a strip of staples being shown in position in sectional view with two of the staples illustrated in side elevational view. Fig. 2 55 is a detail vertical sectional view taken

through Fig. 1 on the line X—X and as seen looking thereat from right to left in the direction of the arrows, the plunger and the spiral operating spring not being seen in this view. Fig. 3 is a detail plan view 60 of the novel improvement for effecting the objects hereinbefore referred to. Fig. 4 is a detail sectional longitudinal view taken through the staple supporting guide-way illustrating my novel improvement as applied thereto. Fig. 5 is a detail plan view 65 as seen looking at Fig. 4 from the top toward the bottom of the drawings.

Referring now to the drawings in detail and first to Fig. 1, 1 and 2 represent the 70 base and pivotal part of the machine and 3 the staple supporting guide-way secured to the part 2 and the base 1 by a pivot pin 4. 5 represents a plunger, 6 the driving head thereof and 7 the spiral operating 75 spring which returns the plunger to its normal position and effects the feed of the staple strip after the staple is severed. 8 represents an inclined lug or shoulder on the rear surface of the plunger adapted to operate against the curvilinear faces of an operating dog 10 pivoted to the machine by a pin 9. To the lower end of the dog 10 is pivotally supported a propelling pawl 11, the feeding end thereof being adapted to 80 have operative connection with the staples of the staple strip. 13 is a holding pawl and 14 is a two-part spring secured to the part 2 with its opposite ends bearing respectively against the under and upper surfaces of the pawls 11 and 13, as shown. 15 represents a strip of staples of well known form, such as is disclosed in connection with either of my prior patents, it being understood that it is only necessary that the feeding and holding ends of the two pawls 11 and 13 shall be constructed to adapt them 85 to any type of staple strip which is generally utilized in the art.

The machine so far described is old and 90 well known and has been in public use for a number of years and its operation will be obvious on inspection of the drawings. My improvement embraces the additional features which will now be described.

I bore a cylindrical hole 18 in one end of the staple supporting guide-way 3 of sufficient diameter to slidingly support a rod 19, and then cut a horizontal transverse slot 16 and a vertical slot 17 at right angles to 110

each other in said guide-way and to the depth shown in the drawings. The rod 19 is provided at one end with an inclined face 20 and lugs 21 of sufficient length and thickness to permit the rod to slide longitudinally in the opening 18 and the lugs in the slot 17 so that the rod cannot turn. To the lower surface of this rod which is flattened near its outer end I secure a two-part spring 25 (see Fig. 1) by soldering, brazing, or in any preferred way, the outer ends of said two-part spring bending upward for a definite distance and then turning downward so as to assume the angular position shown by the numerals 26, 26 (see Figs. 3 and 4) said angular parts being in substantial alinement with the inclined face 20 of the rod 19 and corresponding to the angular face of the teeth of the staples 15 (see Figs. 1 and 2). The rod 19 has a slot 22 near its inner end for the purpose of receiving a pin 23 which also passes through the staple supporting guide-way 3, 24 being a spiral spring normally tending to firmly hold the rod 19 in its outer or forward position with the pin 23 resting against one end of the slot 22. The operation is as follows:—When the staple strip is slipped into position in the manner shown in Fig. 1 the ends of the two pawls assume the position shown behind the second staple and the staple in the outlet beneath the cutting and driving end of the plunger 5 rests with its teeth upon the angular faces 26, 26 of the two-part spring 25. Upon driving the plunger downward by striking a blow upon the head 6 the staple is severed, driven and clenched in the material to be operated upon in a manner well understood. As the plunger descends the lower inclined surface of the lug or shoulder 8 contacts with the lower end of the pivoted operating dog 10 and thereby forces it backward and also forces backward the propelling pawl 11 until the toes of said pawl fall behind the next staple on the strip. As the plunger descends severs and forces the staple downward the inner or cutting edge thereof, acting upon the inclined face 20 of the rod 19, drives it backward against the yielding action of the spring 24 (see Figs. 1 and 4) thereby causing the rod to carry with it the two-part spring 25, so that the angular faces 26, 26 thereof are moved to the rear in the slot 16. As the plunger is lifted, therefore, under the influence of the spring 7 the staple strip is driven forward and the staple which is now shown as being held by the pawls is advanced into the position originally maintained by the staple which has already been driven and clenched, but with sufficient spring pressure from the spring 7 to assure the movement of the strip to its extreme limit. As this occurs the prongs or teeth of such staple pass over the depressed ends of the two-part spring 25 and the latterulti-

mately moves upward at its outer end so that the inclined surfaces 26, 26 now act as a holding means for this staple, as shown in the drawings. It will be apparent also that with this improvement I am enabled to utilize every staple of the strip, for the reason that the inclined surfaces 26, 26 of the two part spring 25 will always hold every staple of the strip in the manner shown in the drawings so that it can be accurately driven and without any possibility of its turning in its descent, as was possible in the use of such strips with the machine disclosed in my first-named Patent No. 572,293.

I do not limit my invention to the details of construction disclosed in the drawings, as obviously the same might be modified in various ways and still bring about the result sought; that is to say, the described manner of holding all staples of a staple strip in the guide-way of a cutting and driving plunger in machines of this type without any relation to the nature of the feeding mechanism by which the strip is fed forward step by step, my improvement being generally applicable to all staple feeding machines heretofore devised where the staples are advanced step by step, and my claims are therefore generic as to holding means for use with such machines.

Although I have shown a two-part spring 25 secured to the rod 19 and adapted to yieldingly hold the staple, obviously this holding part might be relatively rigid and of similar conformation or shape, upon the supposition that there is sufficient elasticity in the staple strip and legs thereof to permit the machine to act in the manner described.

Having thus described my invention what I claim and desire to secure by Letters Patent of the United States is—

1. In a stapling machine of the type described, a staple severing and staple driving plunger for severing and driving two pronged staples from a staple strip; a slideable rod provided with yielding staple holding means adapted to normally rest beneath the prongs or teeth of each staple when the plunger is in its upper or normal position, substantially as described.

2. In a stapling machine of the type described, a staple holding device for the last staple of the strip embracing a staple supporting guide-way, a rod slidably located below the staple strip carried by said guide-way and having an inclined face located in the path of the plunger; together with yielding means for holding said rod in its forward position so that the free or holding end thereof will lie in the path of the last staple when the plunger assumes its normal position, substantially as described.

3. In a stapling machine of the type de-

scribed holding means for the last staple of the strip embracing a slidable rod having angular faces adapted to support the staple in the outlet and a spring for holding said 5 rod in its advanced position; the outer end of said rod having an inclined face adapted to be acted upon by the plunger as it descends, substantially as described.

4. In a stapling machine of the type de-
scribed a holding device for preventing the
last staple of the staple strip from clogging
the outlet of the machine embracing a staple
supporting guide-way, a slidable rod carried
by said guide-way, yielding means carried

by the rod and adapted to lie normally in 15
the outlet, said rod having an inclined face
located under the staple driving plunger;
together with yielding means for normally
holding the rod in its advanced position,
substantially as described. 20

In testimony whereof I have signed my
name to this specification in the presence of
two subscribing witnesses.

EDWIN T. GREENFIELD.
